(57) **CLAIM**

We claim the ornamental design for a tension headband for headaches, as shown and described.

DESCRIPTION

FIG. 1 is a front, top perspective view of a tension headband for headaches showing our design in an open position. FIG. 2 is a front, top perspective view thereof in a closed position.

FIG. 3 is a front elevational view thereof.

FIG. 4 is a rear elevational view thereof.

FIG. 5 is a top plan view thereof.

FIG. 6 is a bottom plan view thereof.

FIG. 7 is a right side elevational view thereof; and,

FIG. 8 is a left side elevational view thereof.
